(57) CLAIM

The ornamental design for a “solar powered rotating stand”, as shown and described.

DESCRIPTION

FIG. 1 is a perspective view of a “solar powered rotating stand”, incorporating my new design, in a first configuration with the display plates removed;

FIG. 2 is a side view thereof;

FIG. 3 is a top plan view thereof;

FIG. 4 is a bottom view thereof;

FIG. 5 is a perspective view thereof in a second configuration with the display plates attached;

FIG. 6 is a side view thereof;

FIG. 7 is a top plan view thereof;

FIG. 8 is a side view of a display plate;

FIG. 9 is a top view of a display plate; and,

FIG. 10 is a bottom view of the display plate.

A single display plate is shown separately in FIGS. 8-10 for completeness of illustration.
